UNITED STATES PATENT OFFICE.

LEWIS S. DUNCAN, OF CHATTANOOGA, TENNESSEE.

ENVELOP-MOISTENER.

SPECIFICATION forming part of Letters Patent No. 781,136, dated January 31, 1905.

Application filed June 22, 1904. Serial No. 213,617.

To all whom it may concern:

Be it known that I, LEWIS S. DUNCAN, a citizen of the United States, residing in Chattanooga, in the county of Hamilton and State 5 of Tennessee, have invented certain new and useful Improvements in Envelop-Moisteners, of which the following is a specification.

This is an improvement in devices for moistening the gummed flaps of envelops.

10 It is an object of the invention to provide an inexpensive, durable, and efficient structure.

An embodiment of the invention is disclosed on the accompanying sheet of drawings, 15 whereon—

Figure 1 illustrates in elevation a device embodying the improvement. Fig. 2 is a plan view showing the application of the envelop, and Fig. 3 is transverse sectional view of 20 Fig. 1.

Similar characters of reference indicate corresponding parts throughout the figures.

I provide a suitable casing 4, constructed of any suitable material and which in the 25 present instance is shown as made of glass, and this casing is provided with a chamber 5 to contain a bath. The inner walls 6 and 7, respectively, of said chamber and on the diametrically opposite sides are provided with 30 an offset 8 and 9, which constitute bearings for journals 10 and 11, carried by a revolving member 12, which in the present instance is provided with a stem 13, having a milled head 14, by which the same may be manually 35 operated. This revolving member in the present instance may be provided with a blanket 15, adapted to be slipped on endwise of said roller and maintained in place and having its ends tucked into a recess 16, Fig. 1, of the 40 revolving member.

As a closure for said casing I provide a lid 17, having an opening 18, through which a portion of the circumference of the roller may extend, and this lid is maintained to the casing by spring-arms 19 and 20, respectively, having portions 21 and 22 suitably offset to take against the under side of the projections 23 and 24 of the casing 4.

Carried by the cover 17 of the casing 4 in 45 the present instance are a pair of uprights

25 and 26, having a connecting-brace 27, and adapted to slide up and down on these uprights is a member 28, having a shoe 29, the under side 30 of which conforms to the circumference of the revolving member 12. This 55 member 28 in the present instance is provided with a lug 31, which is screw-threaded to receive a screw 32 and which is journaled into the cross-bar 27. In this way the member 28 may be raised or lowered by turning the member 33 to any position with relation to the face of the roller 12, so as to accommodate the 60 different thicknesses of paper of which the envelops may be made.

In practice the chamber 5 of the casing is 65 partially filled with water whereby the blanket 15 may absorb the same and the flap of the envelop slipped under the member 28, so that its gummed edge 34 may come in contact with the wet blanket, and thus be moistened for 70 sealing. After a number of envelops have been moistened it will be observed that the blanket will naturally become clogged with the gum, whereupon the thumb-piece 14 may be turned, and thus rotate the roller and 75 blanket until a new and clean portion thereof presents itself to the working point. It will be observed that the edges 35 and 36 of the opening in the lid through which the roller projects is so close to the face of the blanket 80 that during the turning of the thumb-piece 14 such edges will assist in scraping off this gum, which may be suitably removed thereafter, and the balance with which the blanket is impregnated may be soaked out in the bath. 85

The precise construction and arrangement of parts as described and shown herewith need not be necessarily adhered to within the purview of this invention.

It will be observed that I provide a simple 90 construction involving a reservoir and roller mounted therein which is provided with an absorbent blanket and lid for the same and means carried by the lid for pressing the flap of an envelop onto the blanket, so as to moisten the 95 gum edge thereof, and that such device is highly desirable in connection with the sealing of envelops.

It will be observed that aside from moistening the flaps of envelops stamps may also be 100

wet in various ways with this device. One way is to draw a strip of stamps through the device in a manner similar to wetting the flap of an envelop, wetting them all at once, and then tearing them off one at a time as they are applied to the envelop. Another way is to put a corner of the envelop through the device, so as to wet it, and then stamp the envelop on the spot that has been made wet, and, if desired, the lid of the device may be removed and the stamps may be wet one at a time on the roller.

If it is desired to use the device in counting money or turning over leaves of paper, the lid may be removed and the fingers may be dampened on the wet roller.

Having thus described my invention, I claim—

1. An envelop-moistener comprising a reservoir, a roller mounted therein, a removable blanket carried thereby, means for retaining said blanket in place, a lid carried by said reservoir, and having an opening through which said roller projects, the edges of said opening adapted to scrape said roller, and means carried by said lid for pressing an envelop-flap on said roller.

2. An envelop-moistener comprising a reservoir, a roller mounted therein, a removable blanket carried thereby, means for retaining said blanket in place, a lid carried by said reservoir, and having an opening through which said roller projects, the edges of said opening adapted to scrape said roller, and adjustably-mounted means carried by said lid for pressing an envelop-flap on said roller.

3. An envelop-moistener comprising a reservoir, a roller mounted therein, a removable blanket carried thereby, means for retaining said blanket in place, a lid carried by said reservoir, and having an opening through which said roller projects, the edges of said opening adapted to scrape said roller, and means carried by said lid for pressing an envelop-flap on said roller, and means to hold said lid upon the reservoir.

4. An envelop-moistener comprising a reservoir, a roller mounted therein, a removable

blanket carried thereby, means for retaining said blanket in place, a lid carried by said reservoir, and having an opening through which said roller projects, the edges of said opening adapted to scrape said roller, adjustably-mounted means carried by said lid for pressing an envelop-flap on said roller, and means to hold said lid upon the reservoir.

5. An envelop-moistener comprising a reservoir, a roller mounted therein, a removable blanket carried thereby, means for retaining said blanket in place, a lid carried by said reservoir, and having an opening through which said roller projects, the edges of said opening adapted to scrape said roller, means carried by said lid for pressing an envelop-flap on said roller, and spring-clips carried by the lid adapted to snap into place on said reservoir for holding said lid thereagainst.

6. An envelop-moistener comprising a reservoir, a roller mounted therein, a removable blanket carried thereby, means for retaining said blanket in place, a lid carried by said reservoir, and having an opening through which said roller projects, the edges of said opening adapted to scrape said roller, adjustably-mounted means carried by said lid for pressing an envelop-flap on said roller, and spring-clips carried by the lid adapted to snap into place on said reservoir for holding said lid thereagainst.

7. An envelop-moistener comprising a reservoir, a roller rotatably mounted therein, a removable moistening-blanket carried by said roller, means for retaining the blanket in place, a thumb-piece for turning said roller, a lid for said reservoir and having an opening through which said roller projects, the edges of said opening adapted to scrape said roller, a device carried by said lid for pressing an envelop-flap against said roller, a lug carried by said device and a screw-threaded member coöperating with said lug to adjust the pressing member with relation to the roller.

LEWIS S. DUNCAN.
